UNITED STATES PATENT OFFICE.

ABEL MAGUI, OF NEW YORK, N. Y., ASSIGNOR TO ROYAL ART GLASS CO., A CORPORATION OF NEW YORK.

DESIGN FOR A SPINDLE FOR LAMPS, LIGHTING FIXTURES, OR SIMILAR ARTICLES.

Application filed July 9, 1924. Serial No. 10,100. Term of patent 3½ years.

To all whom it may concern:

Be it known that I, ABEL MAGUI, a citizen of the United States, and a resident of the city of New York, county of Bronx, and State of New York, have invented a new, original, and ornamental Design for Spindles for Lamps, Lighting Fixtures, or Similar Articles, of which the following is a specification, reference being had to the accompanying drawing, forming a part hereof.

The drawing shows a perspective view of the spindle for lamps, lighting fixtures, or similar articles.

I claim:

The ornamental design for a spindle for lamps, lighting fixtures, or similar articles substantially as shown.

ABEL MAGUI.
